VIBRATORY EARTHWORKING ROLLER

Clyde W. Wood, Pasadena, Calif.

Application November 5, 1948, Serial No. 58,545

11 Claims. (Cl. 94—48)

1

This invention relates to road making equipment and more particularly to roller constructions employed in compacting road surfacing materials.

It is a common practice in road making to draw some form of heavily weighted roller structure over loose materials which have been freshly placed upon a roadway so that such materials may be forced into a desired compact relationship. This practice is followed in the preparation of dirt fills, crushed rock foundations, various foundation aggregates, oiled earth compositions used for top layers, asphaltic mixtures employed as uppermost surfacing layers, and the like. However, when rolling down applications of most of these layer-forming materials, it would be preferable if all them could be compacted to a much greater degree than has been the current operating practice.

As one aspect of this invention, I have discovered that roller structures employed for compacting road surfacing materials in operative position upon roadways may be made more efficient by incorporating therein means which impart a powerful vibratory action to the roller, inasmuch as such a vibratory roller structure, when drawn across the applied layer of road forming material renders much more dense the resultant compacted layers, and as a consequence produces a more durable and a more serviceable highway.

It is, therefore, an object of this invention to provide a road working roller construction provided with means for vibrating the structure as it is drawn over surfacing material applied to a roadway so that the surfacing material is compacted to a much greater degree than is possible by action of the mere weight of the roller structure.

It is also an object of the invention to employ high speed rotary mechanical means, such as eccentrically mounted weighting masses, to effect the desired vibration.

Another object of the invention is to provide means which will control the vibration so that it may be applied in desired directions with respect to the surface of the roadway, and it is an incidental object to control the resultant vibration and apply it as required for best effect.

Still another object of the invention is to use the axle means upon which an earth working roller is mounted as a means through which the vibratory influences are imparted.

An additional object is to employ means eccentrically mounted adjacent the axis of the

2

earth working roller and adapted to be power driven by way of the roller's axle for the application of the vibratory movements and impulses.

5 Other objects of the invention and the various features thereof, will become apparent to those skilled in the art upon reference to the following specification and the accompanying drawings wherein certain embodiments of the invention are disclosed by way of illustration.

In the drawings:

Fig. 1 is a side elevation of an earth working roller embodying the improvements of this invention;

15 Fig. 2 is a top plan view of the structure shown in Fig. 1;

Fig. 3 is a transverse vertical section taken from the line 3—3 of Fig. 1;

Fig. 4 is a vertical sectional as indicated by the line 4—4 of Fig. 3;

Fig. 5 is a vertical section similar to that of Fig. 4 but illustrating a modification of the vibration-producing means for the earth working roller; and

25 Fig. 6 is a fragmentary longitudinal section as indicated by the line 6—6 of Fig. 5.

The drawings illustrate a road engaging roller 10 mounted upon and supporting a chassis or frame 12 which in turn supports a power plant 14 from which are driven means within the roller 10 for producing the required vibratory effect.

Having particular reference to Fig. 3, one power plant 14 is illustrated as comprising an internal combustion engine 15 of conventional construction which is used in conjunction with a conventional radiator 16 and serves to actuate any appropriate transmission means contained within a conventional transmission housing 18 equipped with a conventional clutch shifting lever 20 or other appropriate power controlling device.

The implement frame 12 may comprise side rails 21 of I-beam construction as illustrated and such cross rails as required. These include forward cross rails 22 upon which the power plant 14 is mounted and its rearward cross rail 22a. In the form illustrated, the forward portion of the frame 12 carrying the power plant 14 is offset downward with respect to the rearward portion of the frame 12, the parts being appropriately connected and braced as through the medium of angularly disposed, intermediate frame sections 21a shown in Fig. 1. This arrangement serves to lower the power plant 14 somewhat with respect to the road engaging roller 10. The forward

portion of the frame 12 is conveniently provided with converging tongue members 23 which carry at their forward, contacting ends any appropriate hitch 24 for connection of the roller structure to a tractive implement by means of which the roller is drawn along the surface being prepared, the most forward cross rail 22 bracing the rearward portion of the tongue structure.

The frame 12 is supported from the roller 10 through the medium of elongated, heavy rubber mounts 25, best seen in Figs. 1 and 3. The upper edges of these rubber mounts 25 are mounted in upper brackets 26 carried by the adjacent portions of the side rails 21, and the lower edges of the rubber mounts 25 are carried in lower brackets 27 provided at the edges of bracket plates 27a (Fig. 3) mounted upon the tops of appropriate bearings 28 in which are journaled the opposite ends of an axle 30 for the roller 10.

The roller 10 comprises an outer, road engaging shell in the form of a cylindrical drum 32 which contains within it an inner cylindrical shell 33 constituting an inner frame member, the drum 32 and the shell 33 being rigidly carried by drum heads 34. The heads 34 carry bearing rings 35 constructed to provide journals for bearings 36 on the axle 30. The bearing rings 35 are appropriately secured to the drum heads 34, as by means of the screws 37 shown in Fig. 3. If required, flanged portions of the rings 35 may carry suitable packing 38.

In the form of construction illustrated, particularly in Figs. 3 and 4, the axle 30 is provided within the frame-forming shell 33 with an eccentrically disposed weight 40 illustrated as being an elongated cylindrical mass which revolves within the shell 33 when the axle 30 is rotated in its bearings 28.

Rotation of the axle 30 is effected from a drive shaft 42 which extends from the transmission housing 18 of the power plant 14 and carries appropriate sprockets 43 which receive drive chains 44 or V-belts that pass to and around sprockets or V-pulleys 45 fixed on one end of the axle 30. Thus, by proper actuation of the clutch lever 20 on the transmission housing 18 the chains 44 are energized and the axle 30 rotated in its bearing 28 and also in the bearings 35 of the roller 10. Under these circumstances the eccentric weight 40 fixed on the axle 30 is caused to revolve at high speed. Such a speed may be in the order of 1000 to 5000 revolutions per minute, and as a consequence the eccentricity of the weight 40 produces a high degree of vibration, as hereinafter more fully explained.

In order properly to tension the drive chains 44 or belts, idle sprockets 46 or belt idlers (Fig. 1) may be employed, these being carried as by means of a plunger 47 cushioned against appropriate spring means in a housing 48 mounted upon the adjacent portion of the frame 12. If required to apply additional weight effective upon the road engaging roller 10, a weight box 49 may be mounted upon the rear of the implement frame 12 for the purpose of receiving appropriate ballast.

A modification of the vibration-producing structure shown in Figs. 3 and 4 is illustrated in Figs. 5 and 6. This construction makes it possible to control the direction or plane of applied vibration to a very large extent by providing for rotational balance in a plane at right angles to the desired plane of applied vibration. Here, two sets of cooperating eccentrically disposed weight-masses are employed. In this instance, the

axle 30 carries a plurality of spaced, narrow eccentric weights 40a instead of the single elongated weight 40 of the other form, and these eccentric weights 40a are staggered with respect to a plurality of spaced, narrow eccentric weights 50 which may be of the crescent formation shown in Fig. 5. The eccentric weights 50 are secured to the inner wall of a rotating frame member or carrier illustrated as being in the form of a cylindrical shell 52 occupying the position of the inner shell 33 of the other form. The shell 52 is provided with a head 53 at each end, and each head 53 is mounted upon the axle 30 by means of ball or equivalent bearings 54 somewhat as illustrated in Fig. 6. Each head 53 is provided also with an integral bearing ring 55 which carries ball or equivalent bearings 56 by means of which the respective head 34 of the drum 32 is thus indirectly journaled on the shaft 30. Flanges 58 serve both to retain the bearings 56 and appropriate packing means.

The shaft 30 is adapted to be rotated in the main bearings 28 by means of a bevel gear 60 fixed thereon, and the inner carrier member 52 is adapted to be rotated upon the axle 30 as by means of a bevel 62 journaled upon the shaft 20 through ball bearings 63 or the like and fixed to the adjacent bearing ring 55 of the shell 52. In the form shown two bevel gears 60 and 62 are driven through an intermediate bevel gear 64 from a drive shaft 65 which would be in turn driven from the power plant 14. As an alternative, the shaft 30 could be driven as shown in Fig. 3, in which case the beveled gear 62 would be driven from the beveled gear 60 through the medium of the gear 64 serving as an idler, the shaft 65 then serving as a mounting means for the gear 64.

It will be apparent, that when one of the gears 60 and 62 is driven in one direction, the other is driven in the opposite direction, such counter-rotational relationship being indicated by arrows in Fig. 5. Thus, when the eccentric weights 40a are in opposition to the eccentric weights 50, as illustrated in Fig. 5, the entire vibration-producing unit is balanced, provided the masses of the weights 40a and the masses of the weights 50 are equal as would commonly be the case. However, when the shaft 30 and the carrier member or shell 52 has been rotated 90° from the position of Fig. 5, the eccentric weights 40a are then in apposition, by reason of the fact that they have their centers of mass aligned. At this stage the parts of the vibration-producing unit are in a maximum condition of unbalance and as a consequence the eccentric forces acting to produce vibrational impulses are effective in a plane in which are disposed both the axis of the shaft 30 and the radius in which lie the centers of mass of the eccentric bodies constituting the weights 40a and 50. Thus, in each 360° cycle the weights 40a and 50 are twice in balance and twice in unbalance.

Operation

When the road rolling structure of this invention is to be placed in operation, the hitch 24 is connected to any appropriate tractive implement by which the device may be drawn slowly along the roadway, or tractive means may be applied to the road rolling structure itself, if desired. Prior to moving the roller 10 upon the road surface, the power plant 14 is placed in operation, and when the roller 10 is to be moved upon the material to be compacted, the clutch

lever 20 is shifted to actuate the drive chains 44 and turn the axle 30 in its bearings 28. As the axle 30 turns within its bearings 28, it also turns within the bearing rings 35 of the drum head 34 where the form of structure shown in Fig. 3 is employed. Thus, while the roller 10 is being drawn or propelled forward at a very slow rate, for example $\frac{1}{4}$ -3 miles per hour, the eccentric weight 40 is being revolved within the inner shell 33 at a vibratory rate of speed which may be in the range of 1000 revolutions per minute to 5000 revolutions per minute or other appropriate rate. In actual practice, it has been found that such a high rotating speed of the axle 30 produces in the roller 10 a vibration of a magnitude to compact the underlying road surfacing material to a very much greater degree than is possible when pulling across it a roller structure of the same weight. In fact, the additional compacting action is far greater than can be obtained by increasing the weight of the roller structure to any practicable extent. As a consequence of rolling down a layer of road surfacing material with a roller equipped with the described vibrating mechanism, a very much firmer and denser layer of surfacing material is produced than possible heretofore, and such surfaces are much more durable and therefore offer much longer service under the pounding of heavy traffic and overloads. In specific instances I have found that the compacting of loose, road surfacing materials spread on a roadway being built or repaired, commonly represents a compacting increase of as much as 20 percent.

When using the construction illustrated in Figs. 5 and 6, the impacting impulses are directed very largely in a vertical plane inasmuch as the vibrational influences are directed upward and downward while substantially rotational balance is provided transversely, although important impact is accomplished regardless of the direction of the rotational unbalance. Thus, it is preferable to set up the vibrating apparatus so that the centers of the masses of the eccentric weights 40a on the shaft 30 are in horizontal balance with respect to the centers of the masses of the eccentric weights 50 on the inner wall of the rotating shell 52. As a consequence, rotation of the two sets of eccentric bodies provided by the series of weights 40a and the series of weights 50 through an arc of 90° from either of their positions of transverse balance, results in maximum off-balance, that is, when their centers lie vertically above or vertically below the axis of the axle 30. Thus, in that part of the rotational cycle when all the centers of the masses of the two sets of weights 40a and 50 are disposed vertically downward, the resultant vibrational impulse is downward, and when such centers are disposed upward along a vertical radius, the vibrational impulse is upward, whereas when such centers reach the horizontal they are horizontally opposed and the vibrational impulses become balanced or neutralized. Therefore, the vibrational influences are largely controlled to be operative substantially linearly in a vertical plane in which the axis of the axle 30 is disposed. Stated in other words, in each cycle of 360° rotation, there are two horizontal stages of balance where the centers of masses of the weights 40a are in opposition to the centers of masses of the weights 50 and the whole vibrational unit is balanced so as to yield a substantially neutral condition. Also in each said cycle, there are two alternating stages of maximum unbalance, that

is, when the centers of the masses 40a are in apposition with the centers of the masses of the weights 50. When these centers are up the vibrational impulse is upward, and when they are down the vibrational impulse is downward. Thus, the movement of the eccentric weighting masses are synchronized to yield the desired vibrational conditions.

The speed of the engine 15 of the power plant 10 may be regulated to produce a rate of revolution of the axle 30 and the eccentrically weighted shell 52 in the form of Figs. 5 and 6 to correspond best with the natural period of vibration of the apparatus as a whole. If necessary, the weight 15 in the weight box 49 may be varied to effect the required vibratory conditions. The elongated, heavy rubber mounts 25 between the implement frame 12 and the mountings of the rolls 10 adequately absorb any objectional transmission vibration between the roller 10 and the frame 12 that might otherwise take place.

In a similar manner, the speed of the engine 15 may be adjusted to cause the rotational speed of the shaft 30 and its eccentric weight 40 in the form of Fig. 3 to conform properly with the vibration period of the apparatus as a whole and thereby establish optimum operating conditions.

Inasmuch as variations of the generic invention herein disclosed will become apparent to those skilled in this art, it is intended to protect all such modifications as fall within the scope of the patent claims.

I claim as my invention:

1. In combination in a road working device: 35 a roller adapted to engage a road surface and be moved therealong; axle means journaled within said roller; eccentrically disposed weighting means carried by said axle means and adapted to be rotated at speeds to vibrate said roller on said surface; a member rotatable within said roller adjacent and upon said axle means; eccentrically disposed weighting means on said member and rotatable therewith; and means for rotating said member and said axle means in opposite directions.

2. A combination as in claim 1 including co-operating bearing means on said roller and axle means journaling said axle in said roller.

3. A combination as in claim 1 wherein said 50 rotating means comprises gear means for rotating said member and axle means at the same speed.

4. In a combination in a road-working implement: a road surface engaging roller; axle means upon which said roller is rotatably mounted; framework in which said axle means is journaled; carrier means rotatably mounted within said roller about said axle means; eccentrically disposed weighting means carried by said carrier means; power means; and means connecting said power means to said carrier means to rotate said carrier means and its weighting means to vibrate said roller.

5. In combination in a road-working implement: a road surface engaging roller; axle means rotatably mounted in said roller; framework in which said axle means is journaled; eccentrically disposed weighting means fixed on said axle means to cause vibration of said roller upon rotation of said axle means; power means mounted upon said framework; means connecting said power means and axle means to rotate said axle means and its weighting means at vibratory speeds; eccentrically weighted carrier means rotatably mounted upon said axle means

and within said roller; and means connecting said power means to said carrier means for rotating said carrier means oppositely to the direction of rotation of said axle means.

6. In combination in a road working implement: a roller adapted to travel upon a roadway; axle means on which said roller is rotatably mounted; framework on which said axle means is mounted; vibration-producing means mounted on said axle means for imparting vibration effects to said roller when being moved over said roadway; power means connected to said axle means to actuate said axle means and said vibration-producing means; second vibration-producing means movably mounted in said roller adjacent said axle means and movable with respect to the first mentioned vibration-producing means; and means connecting said second vibration-producing means with said power means for actuating said second vibration-producing means.

7. A combination as in claim 6 wherein the actuating connections between said vibration-producing means and said power means are connected with said power means to rotate the two vibration-producing means in opposite directions and move such vibration-producing means successively between positions of opposition and apposition for successively producing conditions of balance and unbalance to effect vibration.

8. A combination as in claim 6 wherein: said second vibration-producing means includes a rotary member and both of said vibration-producing means include eccentrically mounted weighting means respectively carried by said axle means and said rotary member; and drive means is provided connecting said power means with said axle means and said rotary member for rotating said eccentrically mounted means in opposite directions for successively producing conditions of balance and unbalance to effect vibration.

9. In combination in road-working equipment:

a roller adapted to travel upon a roadway; axle means rotatably mounted in said roller; a carrier journaled within said roller upon said axle means; framework means in which said axle means is mounted; power means on said framework means; driving means between said power means and said axle means to drive the latter; vibration-producing means connected with said axle means and driven therefrom; second vibration-producing means carried by said carrier and cooperating with the first mentioned vibration-producing means; and additional driving means between said carrier and said power means for operating both vibration-producing means from said power means.

10. A combination as in claim 9 including gear means connecting the two vibration-producing means for relative movement by said drive means and drive connections into positions of balance and maximum unbalance with respect to each other for producing vibration of said roller.

11. A combination as in claim 9 wherein the two driving means include means connecting said axle means and carrier to actuate said axle means and carrier in opposite directions to effect movement of said vibration-producing means between positions of balance and maximum unbalance with respect to each other to vibrate said roller.
